UNITED STATES PATENT OFFICE.

CLAYTON MARIE VAN ORMAN, OF SHERWOOD, MICHIGAN.

RAILWAY-TIE.

SPECIFICATION forming part of Letters Patent No. 314,158, dated March 17, 1885.

Application filed June 20, 1884. (No model.)

To all whom it may concern:

Be it known that I, CLAYTON M. VAN ORMAN, of Sherwood, in the county of Branch and State of Michigan, have invented a new and useful Improvement in Railway-Ties, of which the following is a full, clear, and exact description.

This invention pertains to improvements in railway-ties; and it consists of the combination of parts and their construction, substantially as hereinafter fully set forth and claimed.

Reference is to be had to the accompanying drawings, forming a part of this specification, in which similar letters of reference indicate corresponding parts in both the figures.

Figure 1 is a longitudinal section of a tie of my improved construction with a rail attached, and Fig. 2 is a cross-section of the same.

A is the tie, the same being formed of sheet metal of suitable thickness and rolled into the semi-cylindrical or curved form shown. B is the saddle, formed of cast metal, preferably, and made with its under surface concave to set closely upon the tie. There are two of the saddles on each tie, attached by means of T form or dovetail lugs *a*, that extend through holes cut in the crown of the tie. The metal is slit and bent down to form the holes, so that lips or flanges *b* are left that, taking into notches of the lugs *a* on two sides, hold the saddles securely down in place, said lips or

flanges being forced or bent into said notches by a suitable tool. The other sides of the lugs are straight and fit the holes snugly, to prevent the saddles and rails from spreading. Upon their upper surfaces the saddles *b* are grooved or countersunk at *c* to receive the flanges of the rails, so as to prevent spreading and relieve the spikes of side pressure. At each side of the groove *c* there are two holes in the saddle for spikes *d*, the holes inclining in opposite direction and extending through the tie, so that tendency of the saddle to rise and the rails to rock is resisted by the clamping action of the spikes. Ordinary railroad-spikes are used. The saddle and tie thus connected are practically one, and there being no bolts or pins cannot be disconnected by ordinary use. The tie is self-tamping, because, as it settles by weight put on it, it gathers and compacts the dirt instead of spreading it, as the ordinary tie does. The sides of the tie being rounding the ballast takes good hold upon it.

Having thus described my invention, I claim as new and desire to secure by Letters Patent—

The combination of saddles *B*, formed with T-lugs *a*, and the sheet-metal ties *A*, having holes with flanges or lips *b* at their edges for locking the lugs, substantially as described.

CLAYTON MARIE VAN ORMAN.
